UNITED STATES PATENT OFFICE.

CARROLL CUTLER MILES, OF LANCASTER, MASSACHUSETTS, ASSIGNOR TO RUTH D. MILES, OF LANCASTER, MASSACHUSETTS, DOING BUSINESS AS MILES KEDEX COMPANY.

SEPARABLE FASTENER.

Application filed July 2, 1926. Serial No. 120,200.

This invention relates to a separable fastener adapted to hold a key, tag, check, or other device. The principal objects thereof are to provide such a separable fastener with means for readily detaching it from the article to be held; to provide it with a head in which an identifying disc can be located; and to provide the head with means by which its parts can be disconnected very readily 5 for the exchange of the disc or the like on which the identifying character or characters appear. The invention also involves a key provided with an identifying disc; the provision of the identifying disc with means 10 by which it will be visible in the dark, and other features of construction as will appear.

Reference is to be had to the accompanying drawings, in which

Fig. 1 is a central sectional view through 20 a separable fastening device constructed in accordance with this invention, showing it as mounted on a plate, wall, or other structure, and with the key or the like held in position;

Fig. 2 is a front elevation of the fastener; Fig. 3 is a rear view of the head; and

Fig. 4 is a sectional view on the line 4—4 of Fig. 3.

I have shown the invention on a scale 30 larger than would ordinarily be employed, for the purpose of illustrating better the parts. This device is to be used for fastening a key, check, tag, or the like, 10 separably to a wall 11 which may be the front or rear of a receptacle, box, wallet or in fact anything of a similar character. I have shown one part of the separable fastener, namely the sheet metal piece 12, having a spring socket 13 as of well known construction. This is not described in detail 35 because I prefer to use these articles now on the market. This socket 13 is designed to receive a convex head 14 having a reduced neck 15 preferably formed of metal and of usual construction. The rest of the parts 40 constitute the features of this invention.

This head in accordance with the present invention is mounted on a plate 16 preferably of polygonal shape, so that it can be 50 operated by a wrench, or usually simply by the fingers, in a very simple way. It is provided with an integral projection 17 at the center which is hollow and provided with an internal screw-thread.

55 Into the internal screw-thread of the

member 16 a screw 20 enters, this screw being located on a head which is the visible part of the device when in use. This head has a metal back 22 shown as provided with two perforations 23 for convenience 60 in operating it by means of a spanner but of course capable of operation in any other way. It is provided with two notches 24 all the way through it.

Surrounding this back 22 is the edge portion 28 of a ring. This ring consists of a piece of sheet metal or other material formed open at the back and having a circular flange 24 at the front extending inwardly. It is provided on the back with two 70 prongs 25 of such size as to pass through the notches 24 when they register, for the purpose of assembling and taking apart.

It will be obvious that these two parts can be put together as shown in Figs. 3 and 4 75 especially. Directly against the head and under the flange 24 is placed an identifying disc 26 having a figure 27 in the form of a numeral, letter, word, or other character, and used for the purpose of identifying the 80 article 10 to which it is applied. This character 27 is provided with a coating of radium compound or paint for the purpose of making it visible in the dark. Beyond it is located a thin disc 29 of celluloid or other 85 transparent material, both the discs being held under the flange 24.

In the use of the device, the head and plate 16 are assembled through an opening in the key or tag 10 and the head is secured 90 down so as to hold these parts to the article 10 so that this article then has the identifying device as a part thereof. It is not removed from the article 10 ordinarily except as it may be desired to change the 95 identifying character. Now this key or other device 10 can be attached to the wall 11 simply by forcing the head 14 into the socket 13 as is well understood in the case of separable fasteners of a certain type. 100 This detachably secures it in that position and it is always provided with this identifying device so that the user will know what it is for.

This device is convenient for use in attaching keys in wallets or other carrying devices therefor, also for various kinds of metallic checks and the like and for various other purposes.

It is of a simple character not likely to 110

get out of order, presents an identification which is seen readily at all times, and there is little or no danger of the identifying device becoming detached from the article on which it is located.

Although I have illustrated and described only one form of the invention I am aware of the fact that many changes can be made therein by any person skilled in the art without departing from the scope of the invention as expressed in the claim. Therefore I do not wish to be limited to all the details herein shown, but what I do claim is:—

As an article of manufacture, a device to be detachably secured in the socket of a detachable fastener and consisting of two

parts, a polygonal plate adapted to be turned by a wrench, having a screw threaded passage in one side and a projection on the other adapted to enter said socket, and a head having a back and a screw for securing it to said plate, a ring around the back provided with an external flange and detachably connected with the back, a disc mounted against the front side of said back and having an identifying character thereon provided with luminous surfaces, and a transparent disc over it held under said flange.

In testimony whereof I have hereunto affixed my signature.

CARROLL CUTLER MILES.
